UNITED STATES PATENT OFFICE.

JOHN P. DERR, OF CLEVELAND, OHIO.

DESIGN FOR A HANDLE FOR FRUIT-JAR WRENCHES.

SPECIFICATION forming part of Design No. 25,457, dated May 5, 1896.

Application filed April 29, 1895. Serial No. 547,570. Term of patent 14 years.

To all whom it may concern:

Be it known that I, JOHN P. DERR, a citizen of the United States, residing at Cleveland, in the county of Cuyahoga, State of Ohio, have invented and produced a new and original Design for Handles for Fruit-Jar Wrenches, of which the following is a specification, reference being had to the accompanying drawings, illustrating the same.

10 My invention relates to designs for handles for fruit-jar wrenches, and its object is a handle that is attractive in appearance and symmetrical in form for wrenches for fruit-jars.

In the drawings, Figure 1 is an obverse view 15 of my design, and Fig. 2 is a reverse view thereof. Figs. 3, 4, 5, and 6 are sectional views of a handle, showing my design, taken on the lines A A, B B, C C, and D D, respectively, of Fig. 2.

The leading feature of my design consists 20 in the straight lever 1, curved near its upper end, as illustrated at 2, and the arm 3 at approximately right angles to the lever 1, as shown. The obverse and reverse, Figs. 1 and

2, show this general outline of the handle to be the same on both sides. The form of the 25 handle in cross-section is shown by Figs. 3, 4, 5, and 6. The lever 1 is flat horizontally, of the form illustrated on the lines A A and B B, and as the lower end of the handle is approached the lever gradually flattens at substantially a right angle to the flattened part 30 on the line B B, as seen in Fig. 6, to the end of the lever. This produces a tapering appearance from the curved part 2 to the lower end of the lever 1, and it is substantially elliptical in cross-section on the line C C. An edge view of the arm 3 is seen in Fig. 3. The inner edge of the curved part 2 of the handle is irregular in outline, as illustrated at 2^a.

What I claim is—

35 The design for a handle for fruit-jar wrenches, as herein shown and described.

JOHN P. DERR.
